UNITED STATES PATENT OFFICE.

ARTHUR M. VAN RENSSÉLAER, OF NEW ROCHELLE, NEW YORK.

HAND-KNITTER'S REEL.

1,278,528.

Specification of Letters Patent. Patented Sept. 10, 1918.

Application filed March 14, 1918. Serial No. 222,305.

To all whom it may concern:

Be it known that I, ARTHUR M. VAN RENSSÉLAER, a citizen of the United States, residing at New Rochelle, in the county of 5 Westchester and State of New York, have invented certain new and useful Improvements in Hand-Knitters' Reels, of which the following is a specification.

This invention is a hand-knitter's reel for 10 holding yarn in hand knitting. The objects of the invention are to produce a simple and practical reel for said use, with a removable bobbin, and to provide the bobbin when removed with a handle by which the bobbin 15 can be conveniently held in one hand while the yarn is wound on the bobbin by the other hand.

In the accompanying drawings forming a 20 part hereof and illustrating my invention in the best mode now known to me,

Figure 1 is a top plan view of my new reel ready for use; and

Fig. 2 is a vertical central section thereof at line 2—2 of Fig. 1.

Fig. 3 is a view of the bobbin handle removed.

Referring to the drawings, the base 1 is provided with an upstanding bobbin-holding spindle 2 which as shown is held in place 30 by its lower threaded end, being screwed into a flanged socket member 3 with which the base is provided. The upper surface of the flange is large enough to form a bearing for the under end member of the bobbin 35 when it is mounted revolvably on the spindle the upper end of which is provided with a knurled head 5 between which and the socket member the bobbin may be braked by adjustment of the spindle in its socket. The 40 form of bobbin is of considerable practical importance in order to facilitate the pulling off by the knitter of yarn wound on the bobbin without interfering with the turning movement of the bobbin as a reel, and without 45 entanglement of the yarn, and without the yarn lapping over the bottom crosshead of the bobbin and bearing on the base. The bobbin in the form now shown may be considered as a vertical lengthwise section of 50 a spool included between two parallel planes, one at one side, and the other at the other side of the bobbin bore. I propose to make this bobbin of aluminum alloy, and the form of bobbin shown is desirable for economy of 55 metal. As shown it comprises a pair of parallel body-forming upright members 6

spaced apart and united at the bottom by a crosshead 7 which on its under side has a dependent tubular projection 8. The members 6 are united at the top by a crosshead 9 that has an upstanding tubular projection 10. The tubular projections are alined and their bores receive the spindle on which the bobbin turns. The crossheads are parallel one with another, and each arm of the under or yarn-supporting crosshead is curved downwardly and outwardly at 11. This crosshead has a total length sufficient fully to support the mass of wound yarn on the bobbin across the bottom of the mass, and the said curvature is found convenient in winding the bobbins. The upper crosshead arms are curved upwardly and outwardly to facilitate the unwinding of the bobbins while the yarn is being knitted, and the top crosshead is made shorter than the under crosshead to facilitate the pulling off of the yarn by the hand knitter. When the yarn is in a mass on the under arm it is the under surface of the mass where not supported by 75 the arms of the under crosshead that tends to sag downwardly so that its under sides will bear against the base, and the purpose of the tubular dependent projection 8 is to keep the lower end of the bobbin sufficiently 80 raised above the base to prevent the sagging yarn from running frictionally on it during the knitting, thereby impeding the desired easy pull of the yarn from the bobbin.

When the bobbin, or any bobbin, is to be 85 wound by hand, it is convenient to provide it with a handle by which the bobbin can be held in one hand while being wound by the other hand. As such a handle permanently 90 fixed to the bobbin would interfere with the 95 yarn during the hand-knitting operation, I provide the bobbin with a detachable handle, preferably but not necessarily constructed as follows, the under crosshead being provided with a side recess 12 midway between its ends 100 on one side of the cross-arm. The under member of the bobbin is made with a recess 12 on its side and with a hole 13 extending lengthwise of the under member. The handle 14 is made of a piece of spring wire 105 looped and having one end portion wound about the other end portion as at 15, the two free ends each forming a jaw, one of which 16 is inserted lengthwise into the hole 13, and the other of which 17 snaps into the 110 recess 12 whereby the cross-head is conveniently gripped and held.

What I claim is,—

1. A hand-knitter's reel comprising a base, a spindle, and a revoluble detachable bobbin on the spindle; and a detachable handle for the bobbin; an end member of the bobbin having a radial hole for reception of a portion of the handle, and the handle having a spring member constructed to bear exteriorly on said end member.
- 10 2. A hand-knitter's reel comprising a base, a spindle, and a revoluble detachable bobbin, the bobbin being provided with aligned tubular extensions for reception of the spindle, the under end of the bottom extension bearing on the base and holding the bottom end of the bobbin above the base; and a head for the upper end of the spindle, such head bearing on the upper end of the upper extension,

and a detachable handle; one of said heads being provided with a handle-receiving opening, and the handle having a member adapted to clamp against the head to hold the handle detachably in place. 20

3. In the structure of claim 2, the bobbin having a central body-forming portion 25 formed at each end with a crosshead, the arms of which are parallel and oppositely curved on their opposed edges in the vertical direction, the under crosshead being longer than the upper crosshead, and each 30 crosshead being formed midway between its ends with a tubular projection.

In testimony whereof I have hereunto set my hand this 23 day of February, 1918.

ARTHUR M. VAN RENSSELAER.
